WINDING MACHINE

Ernest R. Swanson, Cranston, R. I., assignor to
 Universal Winding Company, Boston, Mass., a
 corporation of Massachusetts

Application January 10, 1941, Serial No. 374,002

14 Claims. (Cl. 242—45)

This invention relates to improvements in winding machines for winding cops, cones and other packages of yarn, tread and like strand materials.

By the term "yarn" as used in the following specification and claims is meant any type of strand material and the term "package" is herein used to indicate any wound mass whatever its shape or form.

One object of the invention is to provide a winding machine of the type indicated capable of producing packages having the yarn built up with uniform density throughout the wound mass whereby to improve the form of the package and facilitate free delivery of the yarn therefrom during subsequent processing operations.

Another object of the invention is to provide a machine of the type indicated in which the winding spindle is rotated at a gradually reduced rate of speed to maintain the linear speed of the yarn substantially constant throughout the winding of the package.

Another object of the invention is to provide a machine of the type indicated in which the tension on the strand is maintained constant and the emulsifying of the yarn rendered uniform throughout the winding operation.

Another object of the invention is to provide a machine of the type indicated having an electric motor for driving the winding spindle and means controlled by the growth of the winding for gradually reducing the speed of the motor throughout the winding operation.

Another object of the invention is to provide a machine of the type indicated having speed-controlling means which are simple in construction and efficient in performing the intended function.

Further objects of the improvements are set forth in the following specification which describes a preferred embodiment of the invention, by way of example, as illustrated by the accompanying drawings. In the drawings:

Fig. 1 is a front elevational view of the present improved winding machine showing the electric motor for driving the winding spindle and the means for controlling the speed of the motor;

Fig. 2 is a side elevation of the same; and

Fig. 3 is a diagrammatic view showing the electrical circuit for the driving motor.

In a common type of winding machine embodying a rotary spindle it is the usual practice to rotate the spindle at a constant rate of speed and to deposit the thread or yarn on a tube or other

holder carried by the spindle. It is well known in the art that when yarn is wound on a machine of this type the linear speed or draft of the strand delivering to the spindle is gradually increased due to the constantly increasing diameter of the package being wound. Due to this increase in the linear speed of the strand it is caused to balloon to an increasing extent as it is unwound from the supply bobbin, causing an increase in the tension on the yarn from start to finish of the package. Moreover, as the package increases in size more resistance is offered to the passage of the yarn through the tension-device and as a result the yarn may be subjected to excessive tension and the yarn mass caused to be wound with greater density toward the periphery of the wound package. With packages wound in this manner the outer layers of yarn have a constrictive effect on the inner layers causing hard spots and unevenness which hinder the free delivery of the yarn in unwinding it during subsequent processing operations. In addition to the above faults it has been found that when delicate yarn is wound under progressively augmented tension it is apt to be strained and broken and thus rendered unfit for use. In winding machines of this type the yarn is sometimes passed across a wetted roll which acts to moisten or emulsify it and as its linear speed increases the yarn is gradually subjected to less wetting or emulsifying by the roll.

To overcome the deficiencies mentioned above various means have been employed for gradually relieving or reducing the applied tension on the yarn as its linear speed increases whereby to maintain the tension at the package substantially constant during the entire winding operation. Various devices have also been provided for causing the yarn to gradually contact the emulsion roll to a greater extent as the package builds up and the linear speed of the yarn increases whereby to more uniformly wet or emulsify the yarn. These compensating means, besides being somewhat complicated, require considerable attention on the part of the operator and are not entirely efficient in accomplishing the desired result.

It is the purpose of the present invention to provide a winding machine capable of maintaining the linear speed or draft of the yarn constant throughout the entire winding operation so that the use of such compensating devices is unnecessary. This is accomplished by gradually reducing the rotative speed of the winding spin-

idle in accordance with the progressive increase in diameter of the package being wound.

Referring to the drawings, a well-known type of winding machine is herein illustrated as comprising a box-like frame 2 mounting journals for a winding-spindle 3 and a cam-shaft 4 arranged therebelow in parallel relation thereto. The frame 2 is mounted on a bed 8 which, in turn, may be supported by suitable legs, not herein shown. The winding-spindle 3 is adapted to support a core or yarn-receiver of suitable type, the present drawings illustrating a conical paper or fiber cop-tube C on which the package is wound by traversing the yarn y longitudinally thereof. The yarn y is traversed by a thread-guide 5 mounted on a reciprocating traverse-bar 6 adapted to slide in a guideway 7 on a swinging traverse-frame 10. The traverse-frame 10 is of usual bifurcated construction having legs 11 pivoted on the cam-shaft 4 to adapt the thread-guide 5 to move outwardly away from the winding-spindle as the cop or package is built up thereon.

The thread-guide 5 is reciprocated from a helical cam 12 mounted on and rotated by the cam-shaft 4, the traverse-bar 6 being connected to a crosshead 13 slidable in guide-ways in the traverse-frame 10 and carrying a roller or bowl 14 engaging a helical groove in the traverse-cam. As the cam 12 rotates the traverse-bar 6 and thread-guide 5 mounted thereon are reciprocated to traverse the yarn y back and forth on the cop-tube C in the manner indicated in Fig. 2. The traverse-frame 10 is provided with a depending arm 17 terminating in a counter-weight 18 which tends to resist the swinging movement of the frame as the thread-guide 5 is forced outwardly away from the winding-spindle 3 during the growth in diameter of the package.

The winding-spindle 3 projects rearwardly beyond the frame 2 and carries a pulley 20 loosely mounted thereon. The pulley 20 is adapted to be slid axially into and out of engagement with a clutch-member 19 fast on the spindle. Levers 21 and 22 engageable with the opposite sides of the tapered rim of a disk 23 formed integral with the pulley 20 are provided for shifting the pulley. The levers 21 and 22 are fast on a rod 24 rockably mounted in bearings in the frame 2 and carrying a starting handle 25 at its forward end. The rod 24 also carries a brake-shoe 27 which, when the rod 24 is rocked in counterclockwise direction as viewed in Fig. 1, by means of a spring, not herein shown, engages with a brake-disk 28 on the spindle 3 to arrest the rotation of the spindle. To start the rotation of the spindle 3 the handle 25 and the rod 24 are rocked in clockwise direction, as viewed in Fig. 1, to free the brake-shoe 27 from the disk 28 and cause the lever 21 to slide the pulley 20 to clutch it to the spindle. The rod 24 is releasably held in operative position by means of a lock or detent indicated at 30 in Fig. 1, such locking means being common to machines of the present type and therefore not herein described in detail.

The cam-shaft 4 is driven from the winding-spindle 3 at a reduced rate of speed through suitable gearing enclosed within a casing or housing 33. As herein shown, the spindle 3 carries a pinion 34 which drives a spur gear 35 on the cam-shaft 4 through intermediate gears 36, 37 and 38, see Fig. 2.

In the present improved winding machine means are provided for gradually decreasing the

rotative speed of the winding package during the entire winding operation whereby to maintain the linear speed of the feeding yarn constant. Through this method of winding the tension and the amount of emulsifying agent applied to the strand are maintained substantially uniform throughout the winding operation. The tension and emulsifying device are not herein shown or described since they may be of any suitable construction. The means for driving the spindle at a progressively reduced rate of speed is constructed and arranged as next described.

Mounted on a plate 41 carried by the bed 8 of the machine is an electric motor 40 having a pulley 42 at one end of its armature shaft 39 connected to drive the spindle-pulley 20 through the means of a belt 43. The electric motor 40 may be of the same type as that shown and described in United States Letters Patent to Royal Lee, No. 1,767,146, dated June 24, 1930, and is therefore not herein shown or described in detail. A rotary breaker-disk 45, see Fig. 2, within the motor housing carries a pair of opposed contacts 46 and 47. The contact 46 is carried on the rotating disk 45 and is adapted to move radially outward to a limited extent with respect to the axis of the motor under the action of centrifugal force. When the motor is energized and the armature attains a predetermined maximum rate of speed the contact 46 moves outwardly away from the contact 47 under the influence of centrifugal force and since the contacts are connected in the electrical circuit to the field coils of the motor, see Fig. 3, the circuit is opened and the speed of the motor-armature is retarded. As the speed of the armature is reduced the centrifugal force becomes less and the contact 46 is caused to move into engagement with the contact 47 under the tension of a leaf-spring, not herein shown, to close the electrical circuit through the motor windings. Rotation of the motor-armature thus causes the electrical circuit to be opened and closed intermittently at a rapid rate, the contacts 46 and 47 sometimes making and breaking as many as five hundred times per second. Were the contact 47 fixed on the disk 45 the speed of rotation of the armature would be maintained constant and the winding-spindle 3 rotated at a uniform speed. To progressively reduce the speed of the motor shaft and winding-spindle 3 to maintain the linear speed of the yarn uniform, the present invention contemplates the provision of means for shifting the contact 47 radially inward toward the axis of the motor 40 during the winding of a package on the spindle. Due to this progressive displacement of the contact 47 the gap between the contacts is gradually extended and thus they will remain open for increasing periods of time so that the speed of the motor will be accordingly reduced. As in the United States patent referred to above, the contact 47 is mounted at the end of a spring-arm 48 fastened to the rotating disk 45 with its free end connected to an arm or lever 49 by means of a wire link 50. The lever 49 is pivoted on a pin at the end of an arm 51 projecting laterally from the breaker-disk 45 and its lower end is provided with a convex button 55 positioned in axial alignment with the armature-shaft 39 of the motor.

Mounted for axial sliding movement in a bearing sleeve 56 screwed into the end of the casing 44 of the motor 40 is a plunger-rod 57. The inner

end of the plunger 57 is adapted to contact with the button 55 on the lever 49 to cause it to displace the lever in the manner as explained later. Pocketed within an enlarged bore 58 in the sleeve 56 and surrounding the plunger 57 is a helical spring 60 which engages a shoulder 61 on the plunger 57 to normally urge the latter outwardly or to the left as viewed in Fig. 2. The outer end of the plunger 57 has a knurled head 63 and is formed with a threaded axial bore for receiving the threaded end of a cam-follower stud 65. At the outer end of the stud 65 is a cylindrical head having a diametrical slot cut in its outer face. As shown in Fig. 2 the bottom of the slot is V-shaped in contour to provide a follower point 66 adapted to contact with the curved edge of a cam-plate 70 to be later described. The follower 66 of the plunger 57 is held against the edge of the cam 70 under the action of the spring 60 and the stud 65 may be adjusted axially of the plunger 57 to provide for proper cooperation of the inner end of the latter with the lever 49. This adjustment is accomplished by turning the plunger-head 63 relative to the stud 65 and after the proper length of the plunger 57 has been obtained a check-nut 64 on the stud is set up against the head to hold the parts in adjusted relationship.

An arm 76 fastened to one leg 11 of the traverse-frame 10 by means of screws 77 extends laterally therefrom. Fixedly mounted at the end of the arm 76 is a U-shaped bracket 78 having threaded holes 79 in the ends of its upper and lower arms. The cam-plate 70, previously mentioned, is of arcuate contour in edge view, see Fig. 1, its curvature being concentric with the axis of the cam-shaft 4 on which the traverse-frame 10 pivots. The cam-plate 70 is fastened to the arms of the bracket 78 by means of screws 82 projecting through slots in the ends of the cam-plate and screwed into the holes 79 to provide for longitudinal adjustment of the cam. Referring to Fig. 2, the cam-plate 70 is formed with a curved rearward edge 90 against which the follower 66 of the plunger 57 is yieldingly engaged. During the winding operation, as the package builds up on the spindle 3 the traverse-frame 10 swings outwardly to swing the cam-plate 70 downwardly. Engagement of the cam-edge 90 with the follower 66 of the plunger 57 will therefore slide the latter axially into the motor-casing 44 and through the lever 49 and link 50 the contact-element 47 is caused to be moved inwardly in the manner before explained to retard the speed of the motor and winding-spindle. The cam-edge 90 is so plotted that each increment of swinging movement of the traverse-frame 10 causes the plunger 57 to be slid axially a distance sufficient to displace the contact 47 to the required extent to retard the speed of the motor. In other words, the sliding movement of the plunger 57 is directly responsive and proportional to the growth in diameter of the package being wound.

Spaced along the cam edge 90 are graduations 91 which represent points on the cam which register with the follower point 66 when the winding package reaches certain diameters during its growth. The cam-edge 90 as herein shown is generated on such an arc as to be adapted for use in the winding on a conical cop-tube C such as that illustrated in the drawings or on cylindrical cop-tubes as sometimes employed. At the start of the winding, with the thread-guide 5 bearing against the periphery of

either conical or cylindrical cop-tubes of conventional dimensions the index or zero point on the cam-edge 90 should align with the follower point 66. To effect this relationship between the cam-edge 90 and the follower point 66, the screws 82 are loosened and the cam-plate 70 adjusted vertically of the bracket 78, after which the screws are tightened to secure the cam in its adjusted position. Since the mean outside diameter of a conical tube is substantially equal to the outside diameter of a commonly used cylindrical tube, the same setting of the cam-edge 90 will usually suffice for the winding of either conical or cylindrical packages. When cores or tubes of larger diameter are employed the proper graduation or mark on the cam-plate 70 is positioned in alignment with the follower point 66 in a similar manner. The improved winding machine having been described in detail the method of operation thereof is explained as follows:

Assuming that a conical package is to be wound, a conical cop-tube C is placed on a cop-holder carried by the winding-spindle 3 in the position shown in Fig. 2 of the drawings, the thread or yarn y is drawn upwardly from the supply-bobbin and through a tension-device, not herein shown, and when the yarn is to be emulsified or sized, it is drawn across the wetted roll, not herein illustrated, and thence led over a bail-wire 9 on the traverse-frame 10. The yarn is passed through the eye of the thread-guide 5 and its end fastened to the cop-tube C in the usual manner. The traverse-frame 10 is then rocked manually toward the spindle 3 to cause the thread-guide to bear against the periphery of the cop-tube C. When the package to be wound is the first in a series of similar packages the cam-plate 70 may be adjusted initially on the bracket 78 to effect the proper relationship between the cam-edge 90 and the plunger 57.

The electric driving motor 40 is energized by closing a suitable switch 100, indicated in the diagram, Fig. 3, which causes the current to pass through one field coil 101 of the motor and the brushes 102 and 103 contacting the rotor or armature 104. Current will then flow through the contacts 47 and 46, which are now closed, and through the second field coil 105 to complete the circuit. It will be noted by reference to Fig. 3 that a resistance winding 106 and a condenser 107 are shunted across the contacts 47 and 46 and serve to prevent fusing of the contacts due to the arcing which takes place between their faces during the rapid opening and closing of the circuit in which they are incorporated.

With the motor 40 energized its armature shaft 39 and pulley 42 are rotated at a speed which is controlled by the position of the contact 47 with respect to the contact 46. When the armature shaft 39 attains a predetermined speed the contact 46 is moved away from the contact 47 under the action of centrifugal force and the circuit opened. The motor circuit is immediately closed again by the return of the contact 46 as the centrifugal force is lessened and this rapid opening and closing of the circuit is continually repeated to maintain a predetermined speed of the armature-shaft and the spindle-pulley 20 which is connected for rotation therewith by means of the belt 43.

With the pulley 20 being driven, the winding operation is started by rocking the handle 25 to cause the operating lever 21 to clutch the pulley 20 to the member 19 which is fast on the winding-

spindle 3. As the spindle 3 is rotated the yarn is deposited on the cop-tube C and traversed longitudinally thereof by the thread-guide 5 which is reciprocated from the traverse-cam 12, the cam being rotated from the spindle through the train of gears 34, 35, 36, 37 and 38.

As the winding progresses and the yarn builds up on the tube C to form the package the traverse-frame 10 is gradually swung outwardly to rock the cam-plate 18 downwardly. The position of the thread-guide 5 and cam-plate 18 at the completion of a package P is indicated by dash-lines in Fig. 1. The continuous shifting of the cam-plate 18 causes its edge 88 to act on the follower 66 to gradually force the plunger 57 into the motor casing 44. Through means of the lever 49 and link 58 the contact 47 is gradually displaced radially inwardly away from the contact 48 to widen the gap between the two contacts and thus the speed of the armature shaft and spindle 3 is accordingly reduced. This reduction in the speed of the spindle 3 is continuous and uniform throughout the entire winding operation, being controlled solely by the change in diameter of the package being wound. Since the speed-controlling device is not dependent upon the yardage of thread or yarn wound into the package, threads or yarns of any size may be wound without alteration in the construction or adjustment of the elements of the device.

When the package has been fully wound a suitable sizing device, indicated generally at 31 in Fig. 1, acts to release the locking means 38 to permit the rod 24 to be rocked. The rod 24 acting through the lever 22 will then shift the pulley 20 away from the clutch-member 19 to release the pulley from driving engagement with the spindle 3. Simultaneously with the declutching of the pulley 20 the brakeshoe 21 engages the disk 28 to promptly arrest the rotation of the spindle 3. The wound package may then be doffed from the spindle 3 and a fresh cop-tube applied thereto after which the traverse-frame 10 is returned to initial position for winding another package. Return movement of the traverse-frame 10 toward the winding spindle 3 will cause the index or zero point of the cam-edge 88 to be again positioned opposite the follower 66. The rotative speed of the armature shaft 39 and pulley 20 will be thereby reduced to that required at the start of the next winding operation.

Reducing the speed of the winding package in direct proportion to its growth in diameter has the effect to maintain the linear speed of the yarn constant throughout the winding operation. Through this provision the yarn draws off from the supply bobbin, through the tension-device and across the emulsion element at a uniform rate of speed and therefore the tension applied to the yarn remains constant, breakages in the yarn are eliminated and excessive ballooning of the yarn at its source of supply is avoided. Uniform tensioning and emulsifying of the yarn is thus accomplished without the use of compensating devices as usually provided in machines of the present type.

It will be observed from the foregoing that the present invention provides a winding machine capable of producing yarn-packages of improved quality. By maintaining a uniform tension on the yarn strand the package may be wound with uniform density throughout. That is to say, each layer of yarn will be wound with the same applied tension and therefore the package is rendered more stable and its desired contour

preserved. It will be observed further that the speed-governing or controlling means of the winder is of simple construction and its operating elements are adjustable to meet various requirements.

While the improvement is herein shown and described as embodied in a preferred form of construction it will be understood that various modifications may be made in the structure and arrangement of its parts without departing from the spirit or scope of the invention. Therefore, without limiting myself in this respect, I claim:

1. In a winding machine, a winding-spindle, means for rotating the spindle to wind yarn thereon to form a package, means actuated intermittently by the spindle-rotating means throughout the winding operation for controlling the speed of the spindle-rotating means, and means responsive to the growth in diameter of the package being wound for varying the period of operation of the intermittently-operated means to gradually reduce the rotative speed of the spindle whereby to maintain the linear speed of the winding yarn substantially constant.

2. In a winding machine, a winding-spindle, an electric motor for rotating the spindle to wind yarn thereon to form a package, an electric circuit for the motor, speed-responsive means having relatively movable contacts actuated by the motor in accordance with its speed for intermittently opening and closing the circuit to control the speed of the motor, and means responsive to the growth in diameter of the package being wound for adjusting the speed-responsive means to shorten the period during which the contacts are closed to gradually reduce the speed of the motor.

3. In a winding machine, a winding-spindle, an electric motor for rotating the spindle to wind yarn thereon to form a package, and means for maintaining the linear speed of the winding yarn substantially constant throughout the winding operation comprising an electric circuit for the motor, speed-responsive means having relatively movable contacts actuated by the motor in accordance with its speed for intermittently opening and closing the circuit to control the speed of the motor, and means responsive to the increase in diameter of the package being wound for adjusting the relative position of the contacts of said speed-responsive means to open the circuit for progressively longer intervals to progressively reduce the speed of the motor and spindle.

4. In a winding machine, a winding-spindle, an electric motor for rotating the spindle to wind yarn thereon to form a package, an electric circuit for said motor, a rotary circuit-breaker in the circuit, means for rotating the circuit-breaker in timed relation to the rotation of the spindle, said circuit-breaker being responsive to its rotative speed to intermittently open and close the circuit to normally maintain the speed of the motor substantially constant, and means responsive to the increase in diameter of the package being wound for causing the circuit-breaker to open the circuit for progressively longer intervals whereby to progressively reduce the speed of the motor and spindle to maintain the linear speed of the winding yarn substantially constant throughout the winding of the package.

5. In a winding machine, a winding-spindle, an electric motor for rotating the spindle to wind yarn thereon to form a package, an electric circuit for said motor, a rotary circuit-breaker in the circuit, means for rotating the circuit-breaker in timed relation to the rotation of the spindle, said

circuit-breaker being operated by centrifugal force to intermittently open the circuit, means for operating the circuit-breaker in opposition to centrifugal force for closing the circuit to normally maintain the speed of the motor substantially constant, and means responsive to the increase in diameter of the package being wound for adjusting the circuit-breaker to open the circuit for progressively longer intervals whereby to gradually reduce the speed of the motor to maintain the linear speed of the winding yarn substantially constant throughout the entire winding operation.

6. In a winding machine, a rotary winding-spindle, an electric motor for driving the spindle to wind a package thereon, an electric circuit for the motor, a rotary member driven by said motor, a circuit-breaker in the circuit for the motor, said circuit-breaker being carried by the rotary member and adapted to be operated by centrifugal force to open the circuit, means for operating the circuit-breaker to close the circuit, means for controlling the time interval between the opening and closing of the circuit, and means responsive to the growth in diameter of the package wound on the spindle to operate said last-named means to progressively reduce the speed of the motor throughout the winding of the package.

7. In a winding machine, a rotary winding-spindle, an electric motor for driving said spindle to wind a package thereon, a rotary circuit-breaker, said circuit-breaker being responsive to its speed of rotation for controlling the speed of the electric motor, and a cam movable by and with the growth in diameter of the package to adjust the circuit-breaker to progressively reduce the speed of the motor throughout the winding of a package.

8. In a winding machine, a rotary winding-spindle, an electric motor for driving said spindle to wind a package thereon, an electric circuit for said motor, a rotary circuit-breaker for controlling the speed of the motor, means for adjusting the circuit-breaker to vary the speed of the motor, and a cam movable by and with the growth in diameter of the package to adjust the circuit-breaker to progressively reduce the speed of the motor throughout the winding of a package.

9. In a winding machine, a rotary winding-spindle, an electric motor for driving said spindle to wind a package thereon, a circuit-breaker having a centrifugally operated contact for controlling the speed of the motor, said circuit-breaker being adjustable to vary the speed of the motor, means bearing against the winding package and moved thereby during the growth in the winding, and a cam movable by and with said last-named means to adjust the circuit-breaker to progressively reduce the speed of the winding-spindle throughout the winding of a package.

10. In a winding machine, a rotary winding-spindle, an electric motor for driving said spindle to wind a package thereon, means for controlling the speed of the motor, a plunger for actuating said speed-controlling means, and a cam moved by and with the growth in diameter of the package for actuating the plunger to operate the

speed-controlling means to progressively reduce the speed of the motor throughout the winding of a package.

11. In a winding machine, a rotary winding-spindle, an electric motor for driving the winding-spindle to wind a package thereon, means for controlling the speed of the motor, a member movable to operate the speed-controlling means, a cam for moving said last-named member, means responsive to the growth in diameter of the package for actuating the cam to cause it to operate the speed-controlling means for the motor, and means for adjusting the cam in accordance with the setting of the winding machine for different types of packages.

12. In a winding machine a rotary winding-spindle, a traversing thread-guide for depositing yarn on the spindle to wind a package, an electric motor for driving the winding-spindle and traversing thread-guide, a pivoted traverse-frame for supporting the thread-guide to adapt it to bear against the package and to move away from the winding-spindle with the growth in diameter of the winding, an arcuately-shaped cam plate carried by the traverse-frame in concentric relation to its pivot and having a cam-face thereon, a member engaging said cam-face of the cam-plate to be moved thereby during the pivotal movement of the traverse-frame, and a rotary circuit-breaker having a centrifugally operated contact for controlling the speed of the motor, said contact being adjustable by said movable member to progressively reduce the speed of the motor during the winding of a package.

13. In a winding machine, a rotary winding-spindle, a thread-guide for guiding yarn to wind a package on the spindle, means for traversing said thread-guide, an electric motor for driving the winding-spindle and traversing means, a pivoted traverse-frame carrying said thread-guide, an arcuate cam-plate carried by said traverse-frame in concentric relation to its pivot, said cam-plate having an inclined edge, a slideable plunger engaging the inclined edge of the cam-face, and speed-controlling means for the electric motor adapted to be actuated by the slideable plunger to progressively reduce the speed of the motor throughout the winding of a package.

14. In a winding machine, a rotary winding-spindle, a thread-guide for traversing yarn on said spindle to wind a package, means for reciprocating said thread-guide, an electric motor for driving the winding-spindle and guide-reciprocating means, speed-controlling means for said motor, a pivoted traverse-frame for supporting the thread-guide to adapt it to move away from the winding-spindle during the growth in the winding, an arm projecting from said traverse-frame, an arcuate cam-plate carried by said arm in concentric relation to the pivot of the traverse-frame and adjustable longitudinally thereon, said cam-plate having a cam-face thereon, and a plunger engageable with the cam-face of the cam-plate for movement thereby and connected to operate the speed-controlling means to progressively reduce the speed of the motor throughout the winding of a package.

ERNEST R. SWANSON.
